UNITED STATES PATENT OFFICE

CHARLES W. JEFFRIES, OF LAKE CHARLES, LOUISIANA, ASSIGNOR OF ONE-HALF TO
EARL C. REID, OF LAKE CHARLES, LOUISIANA

PAPER-ROLL ADJUSTMENT FOR TYPEWRITERS, ETC.

Application filed August 27, 1928. Serial No. 302,220.

The object of this invention is the provision of a crosswise adjustment or shift of the paper when arranged between the platen and presser rolls of typewriters, adding machines or the like, and which is especially desirable when the paper is put back into the machine to make correctional work or to make additional work.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a plan view of the platen of a typewriter or like machine embodying my improvement, parts being broken away and parts in section.

Figure 2 is a plan view of the presser roll which normally contacts with the platen.

Figure 3 is a side elevation of the improvement.

Figure 4 is a sectional view approximately on the line 4—4 of Figure 3.

Figure 5 is a sectional view approximately on the line 5—5 of Figure 1.

The side members of a frame for a typewriting, adding machine or the like are indicated in Figure 1 of the drawings by the numeral 1. The members 1 have alining bearings 2 for sleeves 3. The sleeves have continuous grooves that receive therein annular ribs 4 in the bearings. The sleeves pass through suitable openings in the center of the peripherally knurled turning wheels 5 and 6 for the platen 7 on the machine.

There are preferably interengaging lugs and grooves between the wheels 5 and 6 for holding the wheels on said sleeves. Each sleeve has a square bore and received in each of these bores there is the cross sectionally squared trunnions 8 and 9 on the ends of the platen. The trunnion 9 is of a materially greater length than the trunnion 8 and has its end reduced and threaded, as at 10. The outer end of the sleeve through which the threaded end 10 of the trunnion 9 passes is formed with an outwardly directed flange 11 that is designed for coengagement with an inwardly directed flange 12 on a collar 13. The outer end of the collar is provided with an outwardly directed flange 14. Received within the collar, and screwed on the threaded end 10 of the trunnion 9 there is a cross sectionally rounded block 15, and a pin 16 connects this block to the collar 13. Surrounding the collar 13 there is an exteriorly knurled cylindrical cap member 17 that has in its bore oppositely directed longitudinally extending ribs 18 that are received in grooves 19 in the collar 13. The ribs 18 extend a suitable distance from what may be termed the inner end of the cap 17, and the grooves 19 are formed on the thickened outer portion of the collar 13. Between the flange 14 of the collar 13 and the ribs 18 there is a helical spring 20 which forces the cap member 17 toward the wheel 6, and brings the lugs 21 on the said cap member into notches 22 on the outer face of the wheel 6, thereby latching the cap to the said wheel 6.

The presser rolls are disclosed by Figure 2 of the drawings, and include any desired number of rolls 23 proper. The rolls are centrally fixed on a shaft 24 and the shaft 24 is slidably mounted in hanger supports 25. The outer ends of the shaft 24 are provided with removable heads 26 and exerting a pressure between these heads and the outer hangers 25 there are light coil springs 27. The springs 27 normally hold the shaft 24, and

consequently the rolls 23 in one position with respect to the hangers 25 but the springs 27, as stated being light may be easily compressed to permit of the shaft moving longitudinally through the hangers 25. The hangers are 5 spring influenced, in the usual manner to bring the presser rolls against the platen 7 and when the platen is to be shifted laterally with respect to the supporting frame of the machine, it is merely necessary to grasp the 10 cap member 17 to first bring its lugs out of the notches 22. The cap member 17 will, of course, compress the spring 20 and by turning the cap member the ribs thereof engaging in the 15 grooves 19 of the collar 13 will rotate the said collar and the collar being connected by the pin 16 to the block or nut 15 which engages the threaded end 10 of the trunnion 9, will impart a longitudinal movement to the said 20 trunnion, by causing the threaded end thereof to be screwed in the bore of the said nut and consequently will move the platen 7 longitudinally with respect to its supporting frame. The presser rolls are, of course, in contact 25 with the paper and exert a frictional engagement therewith sufficient to cause the said paper to move with the platen 7. The springs 27 between the headed ends of the shaft 24 for the rolls 23 are, as stated, comparatively 30 weak so that the shaft and the rolls 23 will move with the paper and with the platen 7. Thus it will be noted that corrections can be made on the paper either before or after the 35 said paper is drawn off of the platen. By again turning the cap member 17 in a reverse direction to bring its fingers opposite the notches 22 in the platen operating wheel 6 the 40 spring 20 will move the cap member, and the elements associated therewith to their initial position, that is, to a position which will permit of the lugs 21 and the cap member again entering the notches 22 on the wheel 6, so that the platen, paper and rolls will be returned to their initial or normal position. The longitudinal 45 movement of the platen is comparatively slight and as previously stated, the paper will move with the platen and will not be retarded by the presser roll should matter already typed on the paper be arranged to 50 align with other matter to be typed thereon.

Having described the invention, I claim:

1. In a device for the purpose set forth, the combination with a platen roll, having square trunnions on the ends thereof, sleeves 55 having squared bores receiving the trunnions therethrough, supports for the sleeves holding the same from longitudinal movement, a turning wheel on each sleeve, one of said trunnions having a threaded end projecting through the sleeve, a block comprising a nut which is screwed on said end, a collar surrounding the block and having an inner lipped engagement with the sleeve, a cylindrical cap member arranged over the collar, interengaging therewith and having spring means influencing the

said cap in one direction, lugs on the inner end of the cap, and the turning wheel adjacent to said cap having notches to receive the lugs therein, and connecting means between the block and the collar.

2. In a device for the purpose set forth, a platen having trunnions extending from the ends thereof which are square in cross section, a sleeve having a squared bore in which each of the trunnions is received, a support 70 for each sleeve permitting the rotation of the sleeves therein, but holding said sleeves from longitudinal movement, an operating wheel fixed on each sleeve, one of said wheels having its outer face provided with spaced notches, and the sleeve for this wheel having its end projected therebeyond and flanged, the trunnion received in the mentioned sleeve having its end reduced and threaded, a block, having a threaded bore for engaging the end of the trunnion, a collar, having its opposite ends flanged, arranged over and secured to the block, and one of said flanges being in contact with the flanged end of the sleeve, said collar having spaced longitudinal depressions in the periphery thereof, a cross sectionally rounded cap having inwardly extending ribs which are received in the mentioned depressions, spring means contacting between the ribs and the outer flange of the collar for forcing the cap toward the turning wheel and said cap having lugs on the inner end thereof to be received in the notches in the turning wheel.

3. In a device for the purpose set forth, a platen roll and a presser roll frictionally contacting with paper on the platen roll and bearings for both of the rolls and means for imparting a slight longitudinal adjustment of the platen in its bearings and for locking the same so adjusted, said presser roll being longitudinally movable in its bearings and light spring means normally holding the presser roll from such longitudinal movement.

4. In a device for the purpose set forth, a platen roll designed to have a paper arranged thereagainst and a presser roll frictionally engaging with the paper for holding the same against the platen roll, and bearings 105 for both rolls, means operable to cause a slight longitudinal adjustment of the platen roll through its bearings and by virtue of the frictional engagement of the paper and the presser rolls to impart a like movement to the paper and to the presser rolls, a shaft for the presser roll which is slidable through its bearings, headed elements on the ends of the shaft and light spring means surrounding the shaft, contacting with said elements and with the bearings adjacent to said elements for normally retaining the presser roll in one position.

5. A presser roll for the purpose set forth, comprising a plurality of spaced rolls, a 110

shaft on which the rolls are fixed, hangers providing bearings for the shaft and through which bearings the shaft is loosely mounted, headed elements on the ends of the shaft and light coil springs surrounding said ends of the shaft and exerting a pressure between the headed elements and the bearings adjacent thereto for normally holding the shaft and rolls thereon from longitudinal movement through the hangers.

10 In testimony whereof I affix my signature.
CHARLES W. JEFFRIES.
